**BLOCK MODULE FOR BUILDING STATUES,
ART PIECES OR THE LIKE**

Stanley Tigerman, Chicago, Ill., assignor to Stanley
Tigerman, Ltd., Chicago, Ill.

Filed Nov. 24, 1969, Ser. No. 20,229

Term of patent 14 years

Int. Cl. D25—01

U.S. Cl. D18—2

Fig. 4

Fig. 5.

Fig. 6.

FIG. 1 is a perspective view of a block module for building statues, art pieces or the like showing my new design;

FIG. 2 is an elevational view of either end of the block module for building statues, art pieces or the like of FIG. 1;

FIG. 3 is a longitudinal sectional view through the block module for building statues, art pieces or the like taken along section line 3—3 in FIG. 1;

FIG. 4 is a top plan view of the block module for building statues, art pieces or the like of FIG. 1;

FIG. 5 is a bottom plan view of the block module for building statues, art pieces or the like of FIG. 1; and

FIG. 6 is a longitudinal sectional view through the block module for building statues, art pieces or the like of FIG. 1 taken along section line 6—6.

I claim:

The ornamental design for a block module for building statues, art pieces or the like, substantially as shown.
